UNITED STATES PATENT OFFICE.

AUGUST KRAUSE, OF SALINA, KANSAS, ASSIGNOR OF ONE-HALF TO JOHN F. LAUTH AND JOSEPH N. SCHWARTZ, BOTH OF SAME PLACE.

OIL-STOVE.

SPECIFICATION forming part of Letters Patent No. 250,263, dated November 29, 1881.

Application filed August 22, 1881. (No model.)

To all whom it may concern:

Be it known that I, AUGUST KRAUSE, of Salina, in the county of Saline and State of Kansas, have invented certain new and useful 5 Improvements in Oil-Stoves, of which the following is a specification.

My invention relates to improvements in that class of oil-stoves in which the chimney-flues for the lamps are formed in a water-reservoir arranged over the lamps; and it consists in providing the water-reservoir with a series of flues, one for each wick-tube, and arranged each immediately over a wick-tube, and hinging the water-reservoir to the oil-receptacle along one of its shorter sides, the major axes of the wick-tubes and flues lying in the longitudinal direction of the water and oil reservoirs, and the flues fitting over the wick-tubes, and the bottom face of the water-reservoir fitting tightly against the upper face of the air-chamber, whereby the water-reservoir can readily be swung over to trim the wicks or for other purposes, and can be as readily swung back and guided to its proper place with 25 the flues over the wick-tubes.

In the accompanying drawings, Figure 1 is a sectional perspective view of an oil-stove containing my improvement; and Fig. 2 is a perspective view of the stove as combined with 30 a steamer, which is broken open to show the interior.

Similar letters of reference indicate corresponding parts.

A is the base and oil-reservoir; a, the air-chamber. b are the wick-tubes, the major axes of which are arranged in the longitudinal direction of the air-chamber a; and c, the wick-raisers of an oil-stove of usual construction.

B is the water-reservoir, having tubes d 40 formed in its middle portion, the major axes of which are arranged in the longitudinal direction of the water-reservoir and fit snugly over the wick-tubes, and provided at its upper side with a ring, g, that is adapted to receive the usual cooking attachments. The reservoir B is attached to base A by a hinge, f,

and rests on the top plate of the air-chamber a, so that its chimney-tubes d lap over the wick-tubes b. There will be one or more tubes d, according to the number of burners, and it 50 will be seen that they are surrounded on all sides by the water contained in the reservoir. By this construction the heat at the outside of the chimney-tubes will heat the water in the reservoir, and at the same time the convenient use of the stove for cooking purposes is not hindered. A supply of hot water is thus 55 always at hand, and is to be drawn for use through the cock e, provided at the side of the reservoir.

In Fig. 2 a steamer, C, is shown as connected by a pipe, h, with reservoir B, so as to receive the steam therefrom. The pipe h has a section, i, of rubber tubing, to allow convenient separation. In this manner the convenience of the oil-stove is greatly extended.

I am aware that the chimney-flue of a lamp has heretofore been formed in a water-reservoir over the wick-tube of the lamp, and I therefore lay no claim, broadly, to such construction, my invention being confined to the precise construction and compact arrangement of the parts, whereby the water can be readily heated, and at the same time the water-reservoir, with its chimneys or flues, be readily 75 turned at one operation by means of its hinge to trim the wicks or for other purposes.

Having thus fully described my invention, I claim as new and desire to secure by Letters Patent—

In an oil-stove, the combination, with the oil-reservoir A and air-reservoir a secured thereto, and having the wick-tubes b, of the water-reservoir B, hinged to the top of the air-chamber at f and provided with the flues or 85 chimneys d, substantially as described, and for the purpose set forth.

AUGUST KRAUSE.
